(57) **CLAIM**

The ornamental design for a portable compartmented multi-layered re-usable food container, as shown and described.

DESCRIPTION

FIG. 1. is an isometric view showing my new design;
FIG. 2. is a top plan view thereof;
FIG. 3. is a right side elevational view thereof, the left side view is identical.
FIG. 4. is a front elevational view thereof, the rear view is identical.
FIG. 5. is a bottom plan view thereof;
FIG. 6. is an alternate view similar to FIG. 1. with the bottom layer shown; and,
FIG. 7. is an alternate view similar to FIG. 1. with the middle layer shown.
